(57) CLAIM

The ornamental design for a wireless ultra sonic diffuser, as shown and described.

DESCRIPTION

FIG. 1 is a perspective view of a wireless ultra sonic diffuser in accordance with the invention;

FIG. 2 is a front view of the wireless ultra sonic diffuser of FIG. 1;

FIG. 3 is a rear view of the wireless ultra sonic diffuser of FIG. 1;

FIG. 4 is a side view of the wireless ultra sonic diffuser of FIG. 1;

FIG. 5 is another side view of the wireless ultra sonic diffuser of FIG. 1;

FIG. 6 is a top view of the wireless ultra sonic diffuser of FIG. 1; and,

FIG. 7 is a bottom view of the wireless ultra sonic diffuser of FIG. 1.

The broken lines shown in the drawings depict portions of the wireless ultra sonic diffuser that form no part of the claimed design.

1 Claim, 7 Drawing Sheets
